PRIMING APPARATUS FOR INTERNAL COMBUSTION ENGINES

APPLICATION FILED FEB. 22, 1914.

1.126.581.

Patented Jan. 28, 1915.

UNITED STATES PATENT OFFICE.

CLEMENT L. SHOCKLEY AND HARVILA E. STRALEY, OF SPRINGFIELD, OHIO.

PRIMING APPARATUS FOR INTERNAL-COMBUSTION ENGINES.

1,126,581.

Specification of Letters Patent.

Patented Jan. 26, 1915.

Application filed February 28, 1914. Serial No. 821,709.

To all whom it may concern:

Be it known that we, CLEMENT L. SHOCKLEY and HARVILA E. STRALEY, citizens of the United States, residing at Springfield, in the county of Clark and State of Ohio, have invented new and useful Improvements in Priming Apparatus for Internal-Combustion Engines, of which the following is a specification.

10 This invention relates to priming apparatus for internal combustion engines, the object in view being to produce simple priming apparatus which is applicable to any multiple cylinder internal combustion engine, whereby liquid fuel such as gasoline or other hydrocarbon may be forced equally to the combustion chambers of all the cylinders for the purpose of facilitating and insuring the prompt starting of the engine 20 upon the turning over of the crank shaft.

With the above and other objects in view, the invention consists in the novel construction, combination and arrangement of parts, as will hereinafter be more fully described, 25 illustrated and claimed.

In the accompanying drawings: Figure 1 is a side elevation of a multiple cylinder internal combustion engine which is conventionally illustrated, showing the present invention applied thereto. Fig. 2 is a longitudinal section through the pump barrel of the cylinder on an enlarged scale. Fig. 3 is a similar view of the fuel intake manifold of the pump cylinder or barrel. Fig. 4 is a cross section through the pump barrel and manifold in line with the check valves and one of the priming line pipes. Fig. 5 is a detail view of one of the intermediate abutments of the pump cylinder.

40 The apparatus contemplated in this invention comprises essentially a pump barrel or cylinder 1, one end of which is permanently closed by a head 2 shown in the form of a solid plug screwed therein while in the opposite end of the barrel 1 is screwed a plug 3 having a central opening 4 therein through which a reciprocatory piston rod 5 works all as shown in Fig. 2.

At one or more intermediate points in the 50 length of the barrel 1, an abutment designated generally at A is inserted, two of such abutments being shown in Fig. 2. Each of said abutments is of sectional construction as illustrated in Figs. 2 and 5 the 55 abutment comprising the two oppositely arranged disk-shaped members 6, the same be-

ing formed with circular recesses 7 in their inner adjacent faces, into which recesses is inserted a packing washer 8 of leather or like material, the packing washer 8 and the members 6 of the abutment formed with central openings 9 and 10 to receive the piston rod 5 and permit the same to work back and forth through the same. In each of the pump chambers 11 formed by and between the abutments A is a pump piston 12, all of said pistons being mounted on the same rod 5 so that they are equally and simultaneously reciprocated back and forth thereby.

Extending along one side of the barrel or cylinder 1 is a fuel intake manifold 13 which is practically coextensive in length with the pump barrel and which is provided with a number of outlet ports 14, there being one of such ports for each cylinder of the engine. Each of said ports 14 is controlled by a check valve 15 shown in the form of a ball resting in a valve chamber 16 so that it will seat against back pressure but allow the fuel to pass to the cylinders by the means hereinafter described. One end of the manifold 13 is left open to provide an inlet orifice 17 to which is connected one end of a fuel supply pipe 18 which, in the preferred embodiment of the invention extends to and connects at 19 to the fuel feed pipe 20 which leads from the supply tank (not shown) to the carburetor designated at 21. The inlet orifice 17 is controlled by a cut-off valve 22 which is movable toward and away from a seat 23 adjacent to said orifice, the valve 22 being operated by means of a manually controlled stem 24 which leads through an opening in the opposite end of the manifold 13, said stem 24 being preferably made of sufficient length to extend rearwardly through the dash 25 of the vehicle where it is provided with an operating handle 26. The piston rod 5 likewise extends rearwardly through the dash 25 and is provided with an operating handle 27. The manifold 13 is also provided with a series of discharge nozzles 28 corresponding to the number of cylinders of the engine and each containing a back pressure check valve 29 which is preferably spring loaded as shown at 30. From the nozzle 28, a priming line pipe 31 extends to one of the cylinders of the engine which is conventionally shown at B. Preferably, each pipe 31 is connected to one of the priming cups 32 of the engine, such priming cup being illustrated in Fig.

1 as being formed in ~~one~~ with the spark plug. Communication between the pump barrel or cylinder 1 and the manifold 13 is formed by ports 33 arranged at suitable intervals and points. The valves 14 are prevented from becoming displaced by means of stops 34 shown in the form of pins which overlie said valves.

10 The priming apparatus hereinabove described is designed to be used either with or without the usual electric or other starter. The apparatus of this invention insures the supply of an equal quantity of fuel to each cylinder of the engine. It has been found 15 that a single pump for a multiple cylinder engine will not introduce an equal amount of fuel into each cylinder for the reason that there is more compression in one cylinder than in another and the fuel will follow 20 the line of least resistance thereby over-priming one or more cylinders and under-priming others. By transmitting the proper amount of fuel to each cylinder, the fuel is atomized as it passes through the inlet cups 25 and formed into a vapor which fills the combustion chamber of each cylinder with a gaseous mixture; furthermore, the force of the fuel as it enters the combustion chamber adjacent to the spark terminals, removes 30 soot and carbon from said terminals and thereby assists in preventing short circuiting and also insures an efficient spark. When used in connection with electric or 35 other starters, the engine will pick up on the first turn or partial turn of the crank shaft thus effecting a material saving in electric current. Furthermore, the priming apparatus will not interfere in the slightest with the motor taking up its usual supply of 40 gaseous mixture from the carburetor.

The pump and the cut-off valve are operable by the driver without leaving his seat. All he has to do is to open the cut-off valve, give several strokes to the pump and then 45 close the cut-off valve. Then by cranking the engine or operating the starter, the engine will take up its operation immediately.

What we claim is:—

50 1. Priming apparatus for multiple cylinder internal combustion engines comprising

ing a single pump barrel, heads at opposite ends of said barrel, an abutment located between said heads and dividing said barrel into a plurality of pump chambers, a single 55 piston rod extending through said pump chambers and intersecting said abutment and one of said heads, a piston in each pump chamber on said piston rod, a fuel intake manifold communicating with said pump 60 chambers, a fuel supply for said manifold, check valves between said manifold and pump barrel, and priming line pipes leading from said manifold to the cylinders.

2. Priming apparatus for multiple cylinder internal combustion engines comprising a single pump barrel, heads at opposite ends of said barrel, an abutment located between said heads and dividing said barrel into a plurality of pump chambers, a single 70 piston rod extending through said pump chambers and intersecting said abutment and one of said heads, a piston in each pump chamber on said piston rod, a fuel intake manifold communicating with said pump 75 chambers, a fuel supply for said manifold, check valves between said manifold and pump barrel, priming line pipes leading from said manifold to the cylinders, and check valves controlling said priming line 80 pipes.

3. Priming apparatus for multiple cylinder internal combustion engines comprising a single pump barrel, heads at opposite ends of said barrel, an abutment located between said heads and dividing said barrel into a plurality of pump chambers, a single piston rod extending through said pump chambers and intersecting said abutment and one of said heads, a piston in each pump 90 chamber on said piston rod, a fuel intake manifold communicating with said pump chambers, a fuel supply for said manifold, and a cut-off valve at the receiving orifice 95 of said manifold.

In testimony whereof we affix our signatures in presence of two witnesses.

CLEMENT L. SHOCKLEY.
HARVILA E. STRALEY.
